ASSEMBLING MACHINE

Harold Lane and Cyril H. James, Leicester, England, assignors to United Shoe Machinery Corporation, Borough of Flemington, N. J., a corporation of New Jersey

Application May 22, 1941, Serial No. 394,688
In Great Britain June 7, 1940

30 Claims. (Cl. 12—4)

This invention relates to improvements in machines for operating on end portions of shoe uppers on their lasts and is herein illustrated as embodied in an assembling machine of the type illustrated in United States Letters Patent No. 1,602,618, granted October 12, 1926, on an application of Norwood H. Knowlton. In certain respects the illustrated machine is similar to the machine illustrated in United States Letters Patent No. 2,057,030, granted October 13, 1936, on an application of Bernhardt Jorgensen. It is to be understood, however, that the invention is not restricted to embodiment in a machine of this particular type, certain features of the invention being of more general application to machines for operating upon shoes.

In assembling certain types of shoe uppers on their lasts, it is desirable to wipe opposite sides of the lasting margin at the heel end of the upper over a sole member on the last and to secure said overwiped portion to said sole member. This applies particularly to the assembling of the uppers of that type of stitchdown shoe in which the lasting margin of the heel end of the shoe is lasted inwardly over a heel piece. In a machine for performing an assembling operation such as that above described, it is desirable that provision be made for pulling up the quarter lining at opposite sides of the heel end of the upper, preferably by means of hand pincers, in order to eliminate any wrinkles that may have occurred therein.

It is an object of the present invention to improve machines of the type described in the Knowlton patent above referred to to adapt them to operate in a satisfactory manner in the performance of an assembling operation such as that above described.

In common with machines of the type above referred to, the illustrated machine is provided with a work support constructed and arranged to yield in the direction of the height of the last in order to permit the last and the upper thereon to be located in predetermined heightwise relation to the operating instrumentalities of the machine as the work support moves to position the last lengthwise thereof, the heightwise positioning of the last being effected by a depressor member which acts against the last bottom. In order to leave the bottom of the last unobstructed to facilitate the manual pulling of the quarter lining, the last depressor in accordance with a feature of the invention is constructed and arranged for movement widthwise of the last into a position remote from the last. In accordance with a further feature of the invention the last and up-

per are held in the predetermined heightwise position in which they are located by the depressor by means constructed and arranged to grip the opposite sides of the upper against the last. The 5 illustrated depressor comprises a carrier, an arm mounted on the carrier for swinging movement widthwise of the last and a presser foot mounted on said arm. For moving the depressor into a position remote from the last, yielding means is provided for swinging the depressor arm away from the last. During its operative movement the depressor is held in last engaging position by means comprising a rail and a roll carried by said arm and constructed and arranged to travel on 10 said rail, means being provided for moving said rail in a direction to permit the arm to swing outwardly away from the last upon completion of the operation of the depressor. During the outward or return movement of the work support, said roll acts on the rail to return it to its initial position in which position it is held by a latch engaging the free end of the rail.

As usual in machines of this type, the latter part of the inward movement of the work support 15 is effected by a cam member constructed and arranged to act on the work support. In the illustrated machine in accordance with a further feature of the invention, the operation of said cam member is timed by means operable by the initial manual inward movement of the work support. As herein illustrated, the cam member is held in position to operate on the work support by a latch which is disengaged from said cam member by the initial inward movement of the support.

For wiping the lasting margin of the heel end of the upper in over a sole member on the last bottom, the illustrated machine, in accordance with a further feature of the invention, is provided with a pair of wipers for overwiping the lasting margin at opposite sides of the upper, each wiper having a stop to limit its overwiping movement, a carrier for each wiper, a member on each carrier for clamping the upper against the last, 20 means for applying clamping pressure to said clamping members and means for operating each wiper independently of the other to a limit determined by the engagement of the stop on the wiper with a side portion of the upper. The illustrated machine is provided with automatic means for operating the wipers, and manually operated means for retracting the wipers individually in order to afford the operator an opportunity to pull up the quarter linings at opposite sides of the heel end of the upper.

In the manufacture of certain types of stitch-down shoes, the lasting margin at the heel end of the upper is wiped inwardly over a sole member in the form of a heel piece which is loosely mounted on the bottom of the last. In order to hold such a heel piece in position during the operation of the machine and particularly during the manual pulling of the quarter linings, it has been found desirable to provide suitable means for clamping the heel piece against the last bottom. Accordingly, the illustrated machine is provided with a novel means for holding such a sole member in place on the last bottom comprising a hold-down and means constructed and arranged to operate said holdown as the wiper is retracted to permit the operator to pull up the quarter lining.

For fastening the overwiped margin of the opposite sides of the heel end of the upper to a sole member on the last bottom, the illustrated machine is provided with novel mechanism comprising fastening-inserting members, means for carrying said members towardly of the upper, and means herein illustrated as guide members mounted on the wiper carriers for locating the fastening-inserting members width-wise of the last.

These and other features of the invention will now be described with reference to the accompanying drawings and pointed out in the appended claims.

In the drawings,

Fig. 1 is a left side elevation of a machine embodying the features of the present invention;

Fig. 2 is a front elevation of the lower portion of the machine, with the parts in their rest position;

Fig. 3 is a front elevation of the upper portion of the machine, showing the upper at one side overwiped and the wiper at the other side retracted to permit the operator to pull up the quarter lining;

Fig. 4 is a plan view of the combined wiping and clamping members, certain parts being shown in section on the line IV-IV of Fig. 3;

Fig. 5 is a sectional view taken on a plane indicated by the line V-V in Fig. 2, the parts being in a position different from that shown in Fig. 2;

Fig. 6 is a detail view of parts shown in Fig. 1;

Figs. 7, 8 and 9 are enlarged progressive views illustrating parts of a mechanism associated with the shoe depressing means;

Fig. 10 is a front elevation showing part of the shoe depressing means, a last and upper being shown in section; and

Fig. 11 is an enlarged left side elevation showing parts of a track-driving mechanism.

In Fig. 1 there is illustrated a machine having, in general, the organization disclosed in the patent to Knowlton above identified, to which reference may be had for a detailed description of parts not fully described herein.

The illustrated machine is provided with a base or column 1 to which is pivoted a work support comprising a carrier 3, a tubular member 5 slidably mounted on the carrier and sustained in an elevated position thereon by a light spring (not shown) and a member 7 slidably mounted in the upper portion of the tubular member and having at its upper end a heel pin 9 on which a last may be mounted. The member 7 is supported by a notched sleeve 11 carried by the tubular member 5. As in the machine of the knowlton patent above referred to, the shoe is moved downwardly into correct heightwise relation to

the operating instrumentalities of the machine by means operable by the inward movement of the work support. As herein illustrated, this mechanism comprises a small block 21 (Figs. 1 and 10) 5 pivotally mounted at 23 on the upper end portion of a depressor, herein illustrated as a bent arm 25, adjustably secured to the upper end of an upwardly and rearwardly extending pivot pin 29 (Figs. 2, 7, 8 and 9) to the upper end of an upright bar or carrier 31, the mid portion of which is slotted to embrace one of a pair of trunnions 33 mounted on the tubular member 5. A tension spring (not shown) connects the bar 31 to the carrier 3 and tends to swing said bar about said trunnion into a position of alignment with the tubular member 5. For causing the depressor to move downwardly during its movement inwardly, or to the left as seen in Fig. 1, a forwardly and 10 downwardly extending link 35 is pivotally connected at its upper end to a lug 37 on the machine frame and its lower end is pivoted to the upper end portion of the bar 31. The upstanding member 27 is provided at its lower end with a short, transversely extending arm 39 (Fig. 2) 15 having a small roll 41 mounted thereon. A spring 43 connected between the arm 39 and the bar 31 tends normally to swing the upright member about the pivot pin 29 to carry the depressor away 20 from the shoe support, such swinging movement of the member being restrained, however, by a rearwardly extending curved rail 45, the upper 25 face of which is arranged to be engaged by the roll 41 (Figs. 7 to 9). The upper surface of the rail in its operative position, as seen in Figs. 7 and 8, provides a convexly curved surface for the roll 41 which is so arranged that during the inward movement of the depressor assembly, the member 27 is supported by the rail in an upright 30 position against the action of the spring 43, the curvature of the rail being such that the member 27 is held against movement widthwise of the shoe as the shoe is advanced heelwardly into position to be operated upon by the operating instrumentalities of the machine. The rail is pivoted 35 at 47 (Fig. 8) to a bracket 49 secured to the machine frame and its free end is held in the position illustrated in Fig. 8 by an upstanding latch lever 55 having a groove 53 which receives the 40 free end of said rail, a light tension spring 57 urging said latch lever toward the end of the rail. The rail is swung upwardly into latched position by a spring 59. As the shoe moves heel foremost 45 into position to be operated upon, the roll 41 travels from its position in Fig. 7 to its position in Fig. 8 and during such movement of the roll, the rail is held in its latched position. During the latter part of the movement of the member 27, the rear part of the shoe is brought into engagement 50 with the upper engaging pads, indicated generally at 63 (Fig. 1), and these pads grip the shoe and hold it securely against upward movement. As the member 27 comes to the limit of its movement, a machined surface 61 on said member 27 55 engages a screw 59 at the upper end of the latch lever 55, disengaging said lever from the free end of the rail and permitting the spring 54 to swing the member 27 outwardly away from the shoe and to swing the rail downwardly in its position 60 illustrated in Fig. 9. The construction and operation of the pads 63 which grip the upper against the last and hold the last and upper against heightwise movement after the depressor is withdrawn are fully illustrated and described in 65 70 75 United States Letters Patent No. 2,235,934.

granted March 25, 1941, upon an application filed in the names of Harold Lane and George Hazelton.

After the shoe support has been swung inwardly to position the shoe relatively to the operating instrumentalities of the machine, a cam member or hook 65 (Fig. 1) operates on the work support to move the shoe forcibly into the clamping pads 63 and to hold it against return movement during the subsequent operations of the machine. The hook 65 is similar in its construction and operation to a corresponding hook illustrated in the Knowlton patent above referred to, and as illustrated in said patent, the hook operates mechanism for locking the tubular member 5 of the work support against downward movement to sustain the last for the subsequent tack-driving operations. As herein illustrated, the hook is mounted on a cross-shaft 67 and operated by a spring 69 connected to the bifurcated tail portion 71 of the hook. The hook is normally maintained in an uplifted or retracted position by the engagement of a slabbed-off surface of a cross-pin 75 (Fig. 6) in the bifurcated tail portion 71 of the hook with a latch piece 77 on a vertical rod 79 which is pivoted at its upper end to the rearwardly extending arm of a cam-operated bell crank lever 81 (Fig. 1) pivoted at 83 to the frame of the machine. A tension spring 85 secured at one end to the machine frame and at its other end to the rod 79 serves to hold the rod in such position that the latch piece 77 will remain in contact with the cross-pin 75. In order to release the hook 65 to the action of the spring 69, a rod 15 which serves to limit outward swinging movement of the shoe support has a pivoted tail portion 87 held in position by a small spring 89 (Fig. 6). As the shoe support swings inwardly of the machine the tail portion strikes the lower end portion of the rod 79, swinging said rod and moving the latch piece 77 away from the surface 75 and freeing the hook to the action of the spring 69. This action of releasing the hook is arranged to take place almost as soon as the clamping pads 63 have commenced to wipe the heel portion of the upper towardly.

With a view to wiping opposite sides of the heel portion of the upper inwardly across the shoe bottom, means in the form of combined wiping and clamping members is provided for acting on the upper in locations adjacent the ends of the wings of a molded counter in the upper. Each of said means comprises a block 93 (Fig. 3) carrying a resilient wiping blade 95 on its upper face and having spaced lugs by means of which it is supported on a forwardly extending stud 97 carried on a carrier member 99 supported as hereinabove described. Freely mounted on the stud 97 between the lugs of the block 93 is a swinging arm 101 which carries at its free end a rubber clamping pad 103 arranged to press against and clamp the sides of a shoe upper to the sides of a last. A small compression spring 105 housed between the lower face of the block 93 and a shoulder 107 on the arm 101 serves to urge the arm in such a direction as to cause the clamping pad 103 to be pressed against the upper while at the same time allowing it to yield outwardly to accommodate itself to lasts of varying shapes and sizes. Each wiping blade 95 and the clamping pad 103 are normally arranged to occupy such an outspread position that they do not impede the movement of a shoe into the machine or rearward swinging of the shoe support as

above described, and means is provided for swinging each blade and pad into engagement with a shoe after the shoe support has been swung rearwardly into the machine, this means comprising a vertical rod 108 (Figs. 1 and 2) housed in bearings 109 in the machine frame. The member 99 is secured at its rear end portion to the upper portion of the rod 108 and a torsion spring 111 surrounding the rod tends normally to swing it to operate the wiping blade and clamping pad. In order to hold each torsion spring 111 loaded and each carrier member 99 in a retracted position, the lower portion of each rod 108 is provided with an inwardly projecting arm 113 (Fig. 5) arranged to bear against the forward and upper end face of the upwardly extending arm of a bell crank lever 115 pivoted on a stud 117 in a bracket 119 on the machine frame, there being two such bell crank levers, one for each arm 113. The rearwardly extending arm of each bell crank lever 115 has a roll 121 (Figs. 1 and 5) pivotally mounted thereon which, due to the action of the torsion spring surrounding the rod 108, is arranged to be pressed against the upper face of the hook 65. The hook therefore acts as stop means to prevent the torsion spring 111 from moving the rod 108 and hence acts to hold the wiping blade and the clamping pad in retracted position. When the hook 65 is moved down to carry the shoe support into its final operative position in the machine, each bell crank lever 115 is released to operate the carrier member 99 thereby to cause the wiping blades and clamping pads to act on the upper. To prevent each wiping blade 95 from moving too far inwardly of the machine there is provided on the lower side of each block 93 a projection 123 (Fig. 3) adapted to engage that portion of the upper adjacent to the edge face of the insole or loose seat piece (whichever is being used) on the bottom of the last. With a view to allowing the operator to inspect the upper after it has been wiped over by the wiping blade and to affording him an opportunity to pull up the quarter lining of the upper if desirable, means is provided for retracting each wiping blade and clamping pad while the other wiping blade and clamping pad remain in contact with the shoe. For this purpose the rear end of the rearwardly extending arm of each bell crank lever 115 carries a laterally extending pin 125 (on which the roll 121 is mounted). Said pin is arranged to be held in a slot 127 in the upper part of a vertical rod 129 connected at its lower end to the rear end of a treadle 130 (Fig. 2). During the automatic movements of each bell crank lever 115 under the influence of the springs 111 as above described each pin 125 will move freely in its slot 127 and will thereby communicate no movement to its treadle 130, thus guarding against the possibility of trapping the operator's foot between the treadle and the floor on which the machine is standing. When, however, the wiping blades and clamping pads are in operative position each pin 125 will occupy a position close to the lower end of its slot 127 and, by depressing the appropriate treadle 130, the bell crank lever 115 associated therewith will be swung about its stud 117 and its upwardly extending arm will engage the inwardly projecting arm 113 on the vertical rod 108 which supports the carrier member 99 and swing the rod against the action of the torsion spring 111 surrounding it, thereby moving the wiping blade and clamping pad away from the shoe upper. By maintaining the treadle de-

pressed, the operator will be afforded the opportunity of inspecting the upper and, if need be, he may, by gripping the lining with a pair of pincers, pull the lining into correct heightwise position in which it will be free from undesired wrinkles. After having inspected the upper the operator may then release his foot from the treadle and allow the wiping blade and clamping pad once more to engage the upper.

In the manufacture of some kinds of stitch-down shoes it is customary, instead of using an insole which is tacked to the last bottom in usual manner, to make use of a heel seat piece which extends from the heel end of the last bottom forwardly into the shank portion. This heel seat piece serves to receive the fastenings driven during the heel seat lasting operation thereby to hold the upper in lasted position, and it is usual for this heel seat piece to be assembled loose on the bottom of the last and not attached thereto in any manner. During the gripping of the lining of the shoe upper by the hand pincers as just described the loose heel seat piece would tend to become displaced from position on the bottom of the last and consequently means is provided in the illustrated machine for holding the heel seat piece down against the last bottom during the time a wiping blade and clamping pad are moved away from the shoe upper as above described. This holdown means comprises a vertical presser member 131 (Figs. 1 and 3) the upper end portion of which is received in a sleeve member 133 secured in a bracket 134 mounted on the frame of the machine. A stud 135 passing through a vertical slot 137 in the sleeve member 133 is secured to the upper end portion of the presser member and is received in a slot in the forward end of lever 139 pivoted between its ends to the bracket 134. To the rear end of the lever 139 is secured the upper end of an upwardly extending bar 141. As seen in Fig. 2, at its lower end portion the bar 141 has a transversely extending portion 143 and a downwardly extending portion 145, this latter portion passing close to the outer side of the upper end of the right-hand treadle rod 129. This portion 145 is slotted at 147 and the pin 125 associated with the right-hand treadle rod 129 passes through the slot 147 and serves to guide the bar 141 for vertical movements as will be described. The transversely extending portion 143 is adapted to rest on the upper ends of the treadle rods 129 and the arrangement is such that when the left-hand treadle rod is raised to move the left-hand wiping blade and clamping pad away from the shoe upper this rod will move the bar 141 upwardly, thereby depressing the presser member 131 into engagement with the heel seat piece on the last bottom. Similarly, when the right treadle rod 129 is raised to move the right-hand wiping blade and clamping pad the transversely extending portion 143 will be moved upwardly, moving the presser member 131 downwardly as above described.

For driving a tack through each portion of the upper adjacent the wiping blade 95 so that the shoe may conveniently be removed from the machine in wiped over condition, there is pivotally mounted on the left-hand side of the slide 155 a downwardly extending bent lever 161 (Figs. 1, 4 and 11) having transversely extending portions 163, 163 at its lower end. The left portion 163 extends outwardly of the machine while the right portion extends underneath the slide 155. Connected to each portion 163 by a ball

joint connection 165 is a forwardly extending arm 167 and to the offset forward portion of each arm there is secured a tacker frame 169. Each tacker frame has an upward extension 170 (Fig. 11) and mounted thereon by means of a slot and bolt connection 171 is a driver-guiding member 173 through which passes a downwardly extending tack driver 175. Each tack driver has a universal connection with a head 177 (Fig. 1) which is connected to a driver lever 157. Tacks are fed from a tack pot (not shown) through tack-tubes 179 (Fig. 3) to tack-holding fingers 181 mounted on the lower end portions of the driver-guiding members 173 and are driven from said fingers by the tack drivers 175 during the power operation of the machine. For controlling the positions occupied by the tacker frames 169 just prior to the driving of tacks therefrom in accordance with the positions occupied by the wiping blades and clamping pads after the latter have performed their wiping and clamping functions, the tacker frames 169 are urged towards each other by a tension spring 183 (Fig. 3) connected between the driver-guiding members 173, and each forwardly extending arm 167 (Fig. 4) has a roll 185 rotatably mounted on its underside. Each roll is held by the action of the spring 183 in engagement with the edge face of a forwardly extending guide member or plate 187 (Figs. 3 and 4) secured to the carrier member 99, the shape of the plate being such that forward movement of the tacker frame 169 will also cause it to swing inwardly. It will be realized, therefore, that when the cam-actuated slide 155 is moved forwardly toward the heel end of the upper to cause the combined gripper and wiper to act on the upper the tacker frames will also be moved forwardly and due to the shape of the plates 187 the tacker frames will move inwardly. Since the inward positions of the wiping blades are controlled by the engagement of the small projections 123 thereon (Fig. 3) with the edge of the insole or seat piece and these positions may vary due to the different shapes of insoles or seat pieces assurance is thus afforded that tacks will always be driven through the over-wiped marginal portions of the upper material. Furthermore, each of the tack-holding fingers 181 is urged downwardly by means of a spring 189 (Fig. 11) connected between the finger and the upward extension 170 of the tacker frame 169, thereby giving assurance that when moved over the shoe bottom the nozzles will contact with the shoe upper, yielding upwardly if necessary against the action of the springs to accommodate themselves to the heightwise contour of the shoe bottom.

In case it should be desired to vary the positions of the tacker frames relatively to the wiping blades and clamping pads, provision is afforded in the illustrative machine for adjusting the initial positions of said frames lengthwise of the upper. For this purpose the downwardly extending lever 161 is provided about mid-way of its height with an adjusting screw 191 (Figs. 1 and 11) arranged to abut against a stop pin 193 fixed in the slide 155 and a tension spring 195 is provided for maintaining the adjusting screw against the stop pin. By rotating the screw 191 the lever arm 161 will be moved about its connection with the slide and will move the tacker frames forwardly or rearwardly of the machine depending upon the direction of rotation of the screw.

Since it is desired to afford the operator opportunity to inspect a shoe after the wiping pads

tion in Fig. 7 to return the depressor to its initial position. During the latter part of its movement along the rail, the roll 41 moves across the fulcrum of said rail and acts together with the spring 50 to swing the rail about its fulcrum and into latched engagement with the upstanding lever 55.

In order to reset the clutch-tripping parts the rear end of a pivoted member 199 (Fig. 1) is connected to the lower end of an upwardly extending rod 201 which in turn is connected at its upper end to the vertical rod 79. When the rod 79 is moved by the cam-actuated bell crank lever 81 to release the hook from the shoe support the rod 201 operates through mechanism similar to that provided in the machine of the Knowlton patent above referred to, to reset the clutch-tripping parts.

In the use of the illustrative machine if, after the shoe has been clamped in position, the operator desires for any reason to remove the shoe from the machine for any readjustment of the upper relative to the last, this may be done by operating a forwardly extending handle 203 (Fig. 1) freely mounted on the shaft 87. The handle 203 carries a rearwardly extending arm 205 adapted to be moved into engagement with a laterally extending pin 207 in the tail portion of the hook and by depressing this pin the hook will be raised out of engagement with the shoe support thereby allowing the latter to move to inoperative position. As described above, this movement of the shoe support will move the depressor to inoperative position and the movement of the hook will move the combined wiping blades and clamping members outwardly away from the shoe.

Having thus described our invention, what we claim as new and desire to secure by Letters Patent of the United States is:

1. In a machine for operating on an end of a shoe upper on a last, the combination with a work support constructed and arranged to yield in the direction of the height of the last, said work support being arranged for movement in the direction of the length of the last, of a last depressor operable by such movement of the work support to position the last heightwise thereof relatively to the operating instrumentalities of the machine, said last depressor being constructed and arranged for movement widthwise of the last into a position remote from the last.

2. In a machine for operating on an end of a shoe upper on a last, the combination with a work support constructed and arranged to yield in the direction of the height of the last, said work support being arranged for movement in the direction of the length of the last, of a last depressor operable by such movement of the work support to position the last heightwise thereof relatively to the operating instrumentalities of the machine, and automatic means for moving the depressor widthwise of the last into a position remote from the last.

3. In a machine for operating on an end of a shoe upper on a last, the combination with a work support constructed and arranged to yield in the direction of the height of the last said work support being arranged for movement in the direction of the length of the last, of a last depressor operable by such movement of the work support to position the last heightwise thereof relatively to the operating instrumentalities of the machine, and a carrier on which said depressor is mounted for swinging movement

widthwise of the last into a position remote from the last.

4. In a machine for operating on an end portion of a shoe upper on a last, the combination with a work support, said work support being arranged for movement in the direction of the length of the last, and means for gripping said end portion against the last, of a last depressor operable by such movement of the work support to position the last heightwise thereof relatively to the operating instrumentalities of the machine, and automatic means for moving said last depressor widthwise to the last into a position remote from the last.

5. In a machine for operating on an end portion of a shoe upper on a last, the combination with a work support and means for gripping said end portion against the last, of a last depressor operable by movement of the work support to move it into a position remote from the last.

6. In a machine for operating on an end of a shoe upper on a last, the combination with a work support movable inwardly to present the upper to operating instrumentalities of the machine, of a last depressor comprising a carrier, an arm mounted on the carrier for swinging movement widthwise of the last, a presser foot mounted on said arm, and means whereby the depressor is operated upon inward movement of the work support.

7. In a machine for operating on an end of a shoe upper on a last, the combination with a work support movable inwardly to present the upper to operating instrumentalities of the machine, of a last depressor comprising a carrier, an arm mounted on the carrier for swinging movement widthwise of the last, and a presser foot mounted on said arm, means for swinging said arm away from the last, and means for holding said arm against such swinging movement during the greater part of the inward movement of the work support.

8. In a machine for operating on an end of a shoe upper on a last, the combination with a work support movable inwardly to present the upper to operating instrumentalities of the machine, of a last depressor comprising a carrier, an arm mounted on the carrier for swinging movement widthwise of the last, and a presser foot mounted on said arm, means for swinging said arm away from the last, and means for holding said arm against such swinging movement during the greater part of the inward movement of the work support, said last-mentioned means comprising a rail and a roll carried by said arm and constructed and arranged to travel on said rail.

9. In a machine for operating on an end of a shoe upper on a last, the combination with a work support movable inwardly to present the upper to operating instrumentalities of the machine, of a last depressor comprising a carrier, an arm mounted on the carrier for swinging movement widthwise of the last and a presser foot mounted on said arm, means for constantly urging said arm away from the last, means for holding said arm in a position adjacent to the last comprising a roll carried by said arm and a rail on which said roll travels, and means for moving said rail in a direction to permit the arm to swing outwardly away from the last.

10. In a machine for operating on an end of a shoe upper on a last, the combination with a work support movable inwardly to present the upper to operating instrumentalities of the machine, of a last depressor comprising a carrier,

63 and the combined wiping blades 85 and clamping pads 103 have operated thereon prior to the driving of tacks through the upper, the illustrative machine is provided with a clutch-tripping handle 197 (Fig. 1) arranged to be controlled by the operator instead of being automatically controlled by inward swinging movement of the shoe support as in the case of the machine of the Knowlton patent above referred to. The clutch mechanism on which the handle 197 operates is 10 substantially the same as in the Knowlton machine.

The operation of the illustrative machine on a stitchdown shoe which has a heel seat piece only and not an insole will now be described, but it is to be understood that the illustrative machine is also capable of operating on other types of shoes such as stitchdown shoes of the type which have a full size insole. It is also capable of operating on the quarter portions of shoes which are 20 formed separately from their foreparts or vamp portions. The operator will assemble an upper loosely around a last on the bottom of which is loosely positioned a seat piece and will then mount the last on the heel pin 8 of the shoe support. 25 After having ascertained that a sufficient marginal portion of the upper extends beyond the bottom of the last to allow it to be effectively wiped over and tacked to the seat piece the operator will swing the shoe support rearwardly into the machine. As the shoe support is moved inwardly the upright bar 31 moves with it due to the engagement of the trunnion 33 with the slot in the bar which causes the bar to be swung about the pivot pin for the lower end of the said downwardly and forwardly extending link 35. These movements of the shoe support 3 and the bar 31 cause mutual relative approaching movement between the depressor and the shoe on the support until the lower end portion of the bar 31 contacts 30 with the frame of the machine. By this time the depressor will have reached a position approximately over the heel seat portion of the shoe on the shoe support and further movement of the shoe support will cause the link 35 to move rearwardly of the machine about its upper end portion. This in turn will cause downward movement of the depressor causing it to engage the bottom of the shoe to depress the same into convenient position for the operating instrumentalities of the machine to operate on it. The final rearward movement of the shoe support will bring the machined face 61 on the member 27 against the stop pin 59 on the lever 55 in the groove 53 in which the rail 45 is then mounted (Fig. 8). The lever 55 will thereupon be urged backwardly against the action of the light tension spring 57 freeing the rail 45 therefrom. The rail will then be freed for downward swinging movement to allow the upstanding member 21 to be 40 swung about its pivot under the action of the spring 43 (Fig. 2) to carry the depressor away from over the shoe bottom, the position of the parts at this stage being shown in Fig. 9. Further rearward swinging movement of the shoe support 3 will move the rod 15 rearwardly to bring its tail portion 87 into contact with the lower end portion of the rod 19 thereby freeing the hook 65 to the action of the spring 69 and allowing it to move the shoe support further inwardly of the machine. As described above the clamping pads 63 will, during movement of the shoe into the machine, urge opposite side portions of the heel end portion of the shoe upper forwardly to prevent the formation of undesired 45

wrinkles in said portion of the shoe, after which the pads will clamp the upper against its last. Downward movement of the hook 65 will also free the combined wiping blades 85 and clamping pads 103 for inward movement under the action of the torsion springs 111 and inward movements of the blades will be limited by engagement of the projections 23 (Fig. 3) on the underside of the wiping blades 85 with the upper opposite the edges of the seat piece and as a result of the action of the wiping blades on the shoe upper the portions of the upper adjacent the corners or forward portions of the wings of a counter in the upper will be wiped inwardly across the shoe bottom. The operator will then free first one wiping blade by depression of the appropriate treadle and will by the use of hand pincers (indicated by broken lines in Fig. 3) pull the lining of the upper upwardly to ensure that it is in free and un wrinkled condition and then by releasing the treadle will allow the blade once more to move inwardly across the shoe bottom and by the action of this wiping blade together with its associated clamping pad the upper will be clamped in wiped over condition. The position the parts assume upon depression of the treadle associated with the left hand wiping blade is indicated in Figs. 3 and 5. Similarly, the other wiping blade will be released to allow the lining on the other side of the shoe to be pulled up. During the pulling of the lining by the hand pincers the seat piece will be held from movement on the last bottom by the action of the presser foot 121 which is automatically lowered upon depression of either of the two treadles associated with the respective wiping blades. After having ascertained that the upper is in correctly clamped position the clutch-tripping handle 197 will be actuated to set the machine into power-operation. During the power operation of the machine the back seam portion of the lasting margin is pulled up and wiped inwardly over the heel seat piece and tacked thereto. The side tacker frames 168 are then moved both forwardly and inwardly of the machine and guided by contact with the plates 187 (Fig. 4) so that the tacks will be driven through the overwiped margins of the upper. As the machine nears the end of its power operation the cam-operated bell crank lever 81 will be actuated to move the rod 19 first upwardly to carry the latch piece 77 (Fig. 6) thereon beyond the plane surface 78 and will then move the rod downwardly to swing the hook against the action of its spring into inoperative position, the pivoted tail portion 87 of the rod 15 moving against the action of its spring 88 if need be to permit downward movement of the rod 19. At the same time the spring 85 will move the rod forwardly of the machine so that as the machine comes to a stop the parts will be retained in latched condition ready for operation on another shoe. Upward movement of the hook 65 will swing the two bell crank levers 115 about their pivots to rotate the vertical rods 188 against the action of the torsion springs 111 to move the wiping blades and clamping pads away from over the shoe bottom. Release of the hook from the shoe support will allow the latter to swing into its inoperative position, illustrated in Fig. 1, and during this movement the upright bar 31 carrying the depressor-supporting member will by reason of its engagement with the shoe support also be moved forwardly. The roll 41 on the depressor-supporting member will travel along the pivoted rail 45 from its position in Fig. 9 to its pos- 50 55 60 65 70 75 80 85 90 95

an arm mounted on the carrier for swinging movement widthwise of the last and a presser foot mounted on said arm, means for constantly urging said arm away from the last, means for holding said arm in a position adjacent to the last comprising a roll carried by said arm and a rail on which said roll travels, means for moving said rail in a direction to permit the arm to swing outwardly away from the last, said rail being so mounted that it is returned to its initial position by the depressor arm in the course of the return movement of said arm, and a latch for holding the rail in its initial position.

11. In a machine for operating on a shoe upper on a last, the combination with a work support movable inwardly to present the upper to operating instrumentalities of the machine, of a last depressor comprising a carrier movable with said support, an arm mounted on the carrier for swinging movement widthwise of the last and a presser foot mounted on said arm, a roll on said arm, a rail on which said roll travels during the inward movement of the work support and the depressor, said rail being movable to permit the arm to swing widthwise of the last, and a latch for holding the rail against such movement.

12. In a machine for operating on an end of a shoe upper on a last, the combination with a work support movable inwardly to present the upper to operating instrumentalities of the machine and constructed and arranged to yield in the direction of the height of the last, of a last depressor operable by the inward movement of the work support and movable widthwise of the last into a position remote from the last.

13. In a machine for operating on an end of a shoe upper on a last, the combination with a work support movable inwardly to present the upper to operating instrumentalities of the machine, of a cam member operable after an initial inward movement of the work support to impart a further inward movement to said support, and means operable by said initial movement of the support to time the operation of said cam member.

14. In a machine for operating on the end of a shoe upper on a last, the combination with a work support movable inwardly to present the upper to operating instrumentalities of the machine, of a cam member operable automatically after an initial inward movement of said support to impart a further inward movement to said support, and means operated by said initial movement of the support to render the cam member operative.

15. In a machine for operating on the end of a shoe upper on a last, the combination with a work support movable inwardly to present the upper to operating instrumentalities of the machine, of a cam hook operable after an initial inward movement of said support to impart further inward movement thereto, a spring for operating said hook, a latch for holding said hook in position to operate on said support after its initial inward movement, and a member operable by said initial movement of the support to unlatch said hook.

16. In a machine for operating on the end of a shoe upper on a last, the combination with lasting wipers and a work support movable inwardly to present the upper to the wipers, of a cam hook operable after an initial inward movement of said support to impart further inward movement thereto, a spring for operating said hook, a latch for holding said hook in position to

operate on said support after its initial inward movement, a member operable by said initial movement of the support to unlatch said hook, means for returning the hook to its latched position, and means operable by the return movement of said hook to retract the wipers.

17. In a machine for operating on the heel end of a shoe upper on a last, a pair of wipers for overwiping the lasting margin at opposite sides of the upper, each wiper having a stop to limit its overwiping movement, a carrier for each wiper, an upper clamping member pivotally mounted on each carrier, means for applying clamping pressure to said clamping members, and means for operating each wiper independently of the other to a limit determined by the engagement of the stop on the wiper with a side portion of the upper.

18. In a machine for operating on the heel end of a shoe upper on a last, a wiper for overwiping the lasting margin of the upper, automatic means rendered operative by longitudinal movement of the last to actuate said wiper and yieldingly to hold it in overwiped position, and manually operated means for retracting the wiper after it has been actuated.

19. In a machine for operating on the heel end of a shoe upper on a last, a pair of wipers for overwiping the lasting margin of the upper, automatic means rendered operative by longitudinal movement of the last to actuate said wipers, and manually operated means for retracting said wipers individually.

20. In a machine for operating on the heel end of a shoe upper on a last, a pair of wipers for overwiping the lasting margin of the upper, a pair of upper clamping members mounted for movement with the wipers, automatic means for simultaneously operating the wipers and the clamping members, and manually operated means for individually retracting the wiper and clamping member assemblies.

21. In a machine for operating on the heel end of a shoe upper on a last, the combination with a work support movable lengthwise of the last, and a cam member for moving said support, of a wiper for overwiping the lasting margin of the upper, an upper clamping member mounted for movement with the wiper, and means rendered operative by movement of said cam member for automatically operating said wiper and clamping member.

22. In a machine for operating on the heel end of a shoe upper on a last, the combination with a work support movable lengthwise of the last, and a cam member for moving said support, of a wiper for overwiping the lasting margin of the upper, an upper clamping member mounted for movement with the wiper, means rendered operative by movement of said cam member for automatically operating said wiper and clamping member, and manually operated means for retracting said wiper and clamping member.

23. In a machine for operating on the heel end of a shoe upper on a last, a wiper for overwiping the lasting margin of the upper, a hold-down for holding a sole member in place on the last bottom, and means operable to retract said wiper and to operate said hold-down.

24. In a machine for operating on the heel end of a shoe upper on a last, a wiper for overwiping the lasting margin of the upper, a hold-down for holding a sole member in place on the last bottom, and manually operated means for retracting said wiper and operating said hold-down.

25. In a machine for operating on the heel end of a shoe upper on a last, the combination with a work support movable lengthwise of a last mounted thereon, and a cam member for moving said support, of a pair of wipers for overwiping the lasting margin of the upper, means controlled by said cam member for automatically operating said wipers, a holdown for holding a sole member in place on the last bottom, and manually operated means for individually retracting said wipers and for simultaneously operating said holdown.

26. In a machine for operating on the heel end of a shoe upper on a last, the combination with a wiper for overwiping the back-seam portion of the lasting margin of the upper, wipers for overwiping opposite sides of the heel portion of the lasting margin and carriers for said last-mentioned wipers, of fastening-inserting members for securing the overwiped side portions of the lasting margin to a sole, carrying means for said fastening-inserting members movable toewards of the upper, and means positioned by the advancement of said side wipers for locating said fastening-inserting members widthwise of the last.

27. In a machine for operating on the heel end of a shoe upper on a last, the combination with a wiper for overwiping the back-seam portion of the lasting margin of the upper, wipers for overwiping opposite sides of the heel portion of the lasting margin and carriers for said last-mentioned wipers, of fastening-inserting members for securing the overwiped side portions of the lasting margin to a sole, carrying means for said fastening-inserting members movable toewards of the upper, and guide members mounted on the side wiper carriers and constructed and arranged to guide the fastening-inserting members during

their toeward movement and to position them widthwise of the last.

28. In a machine for operating on the heel end of a shoe upper on a last, the combination with a wiper for overwiping the back-seam portion of the lasting margin of the upper, wipers for overwiping opposite sides of the heel portion of the lasting margin and carriers for said last-mentioned wipers, of fastening-inserting members for securing the overwiped side portions of the lasting margin to a sole, carrying means for said fastening-inserting members movable toewards of the upper, guide members mounted on the side wiper carriers and constructed and arranged to guide the fastening-inserting members during their toeward movement and to position them widthwise of the last, and means for adjusting the initial positions of the fastening-inserting members lengthwise of the last.

29. In a machine for operating on an end of a shoe upper on a last, the combination with a work support movable inwardly to present the upper to the operating instrumentalities of the machine, of a cam member for imparting inward movement to said support, and means for retracting said cam member to permit the work support to move outwardly without awaiting the completion of the cycle of operations of the machine.

30. In a machine for operating on an end of a shoe upper on a last, the combination with a work support movable inwardly to present the upper to the operating instrumentalities of the machine, of a cam member for imparting inward movement to said support, and means operable manually at the will of the operator for retracting the cam member without awaiting the completion of the cycle of operations of the machine.
